TRANSFER MECHANISM FOR DUPLEX ADDING MACHINES, CASH REGISTERS, ETC.

Original Filed May 26, 1923

Fig. 2

UNITED STATES PATENT OFFICE.

ERNST KASSNER, OF BERLIN, GERMANY.

TRANSFER MECHANISM FOR DUPLEX ADDING MACHINES, CASH REGISTERS, ETC.

Original application filed May 26, 1923, Serial No. 641,650. Divided and this application filed September 22, 1926. Serial No. 136,942.

This invention relates in general to decimal stepping devices for calculating machines, more particularly for machines of the kind described in my co-pending application Serial No. 641,650 filed May 26th, 1923, of which this application is a division, which machines comprise two counting trains.

The object of this invention is to provide 10 a novel decimal stepping device for such machines whose gearing is of very simple construction and can be depended on to act perfectly accurately. This is accomplished by combining the rocking arms of the stepping pawls of corresponding digits of the 15 two counting trains by links which are moved at each revolution of the main operating shaft of the machine. Other features of the invention will appear hereinafter.

20 The invention is illustrated in the drawing in which

Fig. 1 is a section of the counting trains on a plane extending from the front to the back of the machine and

25 Fig. 2 is a transverse section extending at right angles to that shown in Fig. 1.

The counting trains 1 and 2 are mounted on the shafts 3 and 4, and arranged between the counting trains 1 and 2 on a shaft 5 are 30 intermediate toothed driving wheels 6 which can be brought into engagement with either of the counting trains by swinging the shaft 5 to and fro. To this end the rockable shaft 5 is mounted at the upper end of a rocker 35 frame 7 that can be swung on a pivot or shaft 8 towards the left or right counting train as desired. The connecting line between the centers of the shafts 8 and 5 is shown in its furthest right hand position in 40 Fig. 1, i. e. in the position in which the intermediate wheels 6 are in mesh with the right hand counting train 2. When the rocker frame 7 is turned through the angle 9 to the left, the intermediate wheels engage 45 with the left hand counting train 1. The intermediate wheels 6 are turned in accordance with depressed keys (not shown) by a setting gear (not shown) and the numerical values that correspond to the depressed keys 50 and are indicated or recorded on the one counting train or the other according to the position of the rocker frame 7.

Each of the two counting trains has a 55 number of counting disks or number disks 1 and 2 that is equal to the number of digits

provided for. Fixed to each number disk is a stepping wheel 10, 11 and a toothed gear wheel 12, 13. The intermediate wheels 6 can be made to engage with either the gear wheels 12 or the gear wheels 13, so that in 60 one case the left counting train or in the other case the right hand counting train is operated. The stepping wheels 10, 11 are engaged by detents 14, 15 which hold the number wheels 1, 2 in the position into which 65 they have been turned.

The decimal stepping device for the left hand counting train 1 is arranged on the rockable shaft 5 and consists chiefly of the two-ended rocking arms 16 whose number 70 corresponds to the number of digits in the train and to whose upper short ends tens stepping pawls 18 are attached by pivots 17. The stepping pawls 18 are generally held in uplifted or inoperative positions by locking 75 members or dogs 19. Each stepping pawl 18 and its associated dog 19 are interconnected by a draught spring 20.

A similar decimal stepping device is provided for the counting train 2 and mounted 80 on a separate shaft 21. It consists of two-ended rocking arms 22, tens stepping pawls 24 connected by pivots 23 to these arms, dogs 25, and draught springs 26 that connect the pawls and dogs. 85

A feature of the invention is that the two rocking arms 16 and 22 of each digit are interconnected by a separate link 27, so that the number of links corresponds to the number of digits in a counting train. At each 90 revolution of the main operating shaft these links are shifted in the direction of their length and transmit motion to the decimal stepping mechanisms, because each link 27 is connected by a pivot 28 to an actuating member in the form of rocker plate 29 that is journaled on a shaft 30. Each rocker plate 29 has an anvil arm 31 that lies in the path of one of the striker arms or cams 33 fixed on the shaft 32 so as to be radially 95 displaced with respect to each other. The operating shaft 32 is geared by wheels (not shown) to a main operating shaft and revolves once at each operation of the machine. At each revolution of the shaft 32 the cams 100 33, whose number is equal to the number of digits, strike in succession against their corresponding anvil arms 31 on the rocker plates 29, so that the rockable arms 16 and 22 each execute one swinging motion when 105 110

the main operating shaft is turned. As long as the dogs 19 and 25 are in their uplifted positions this swinging motion has no effect on the counting trains.

5 But when one of the counting trains 1 or 2 steps past the nine, a striking pin 34 or 35 on the particular number disk in question comes into contact with a projection 36 or 37 of the dog 19 or 25 and disengages the 10 same from its stepping pawl 18 or 24 so as to release it. The dog 25 of the right hand counting train is shown in Fig. 1 in its disengaged position by broken lines 25'. As soon as the dog is shifted into its disengaged position the associated stepping pawl 24 is pulled downward by its spring into the position indicated by broken lines 24' and when the rockable arms 16 and 22 are now deflected by the revolution of the 20 main operating shaft the stepping pawl 24' engages with the stepping wheel 11 of the associated number wheel or disk 2 and turns it round to the next number. When the number wheel turns further around its striking pin 34 or 35 lifts the dog 19 or 25 up again into the position in which it locks the stepping pawl in its inoperative position.

As the decimal stepping device of the left hand counting train 1 is arranged on the 30 rockable shaft 5 journaled in the rocker frame 7 there is a danger that when the frame 7 is rocked, that is when the intermediate arms 6 are disengaged from one train and brought into engagement with the 35 other, the position of the rockable arms 16 and 22 will be affected in such a way as to prevent the decimal stepping device from operating properly. To obviate this danger the following arrangement is made: The 40 pivot 38 by which the link 27 is connected to the rockable arm 16, is positioned so that it lies on the line 39 which bisects the angle 9 through which the rockable shaft is swung in its supporting frame or rocker frame 7. By this arrangement the rocking of the 45 frame 7 is prevented from affecting the position of the two rockable arms 16 and 22, or at any rate there will be practically no measurable alteration of their position, because the point 38 remains in its position 50 of the line 39 that divides the angle 39 into two halves.

I claim:—

1. A decimal stepping device for machines 55 of the kind described, comprising two multi-digit counting trains, a stepping wheel for each digit of each train, a stepping pawl for each stepping wheel, a rocking arm for each stepping pawl, a link between each 60 rocking arm of one counting train and the

rocking arm of the corresponding digit of the other counting train, a revolute main operating shaft for the machine, and means for rocking either of said links with its rocking arms at each revolution of the operating shaft. 65

2. A decimal stepping device for machines of the kind described, comprising two multi-digit counting trains, a rockable shaft, a rockable supporting frame for supporting the rockable shaft, driving wheels on the rockable shaft for driving one or the other counting train according to the position into which the rockable frame is rocked, a stepping wheel for each digit of each counting train, rocking arms, one for each stepping wheel of one counting train mounted on said rockable shaft, further rocking arms, one for each stepping wheel of the second counting train, stepping pawls, one for each of said stepping wheels, pivotally attached to said rocking arms; a link between each rocking arm of the first counting train and the rocking arm of the corresponding digit of the other counting train; a revolute operating shaft for the machine; and means for rocking either of said links with its rocking arms at each revolution of the operating shaft. 75

3. A decimal stepping device for machines of the kind described, comprising two multi-digit counting trains, a rockable shaft, a rockable supporting frame for supporting the rockable shaft, driving wheels on the rockable shaft for driving one or the other counting train according to the position into which the rockable frame is rocked, a stepping wheel for each digit of each counting train, rocking arms, one for each stepping wheel of one counting train mounted on said rockable shaft, further rocking arms, one for each stepping wheel of the second counting train, stepping pawls, one for each of said stepping wheels, pivotally attached to said rocking arms, a link pivotally attached between each rocking arm of the first counting train and the rocking arm of the corresponding digit of the other counting train, the pivot of the link on the rocking arm mounted on said rockable shaft lying on a line which halves the angle through which the rockable shaft is swung in its supporting frame, a revolute operating shaft for the machine, and means for rocking either of said links with its rocking arms at each revolution of the operating shaft. 90

In testimony whereof I have signed my name to this specification.

ERNST KASSNER.
